UNITED STATES PATENT OFFICE.

ISAAC F. GILES, OF YONKERS, NEW YORK, ASSIGNOR TO ILEITE ELECTRIC MANUFACTURING CORPORATION, OF TUCKAHOE, NEW YORK, A CORPORATION OF NEW YORK.

MULTIPLE SOCKET.

Application filed June 15, 1925. Serial No. 37,029.

This invention pertains to multiple socket electric fixtures, particularly to a two or three way socket where the casing comprises molded electrical insulating material. One

5 of the difficulties arising in connection with the manufacture of such fixtures is the necessity for soldering the connections within the casing so as to provide a rigid construction and to insure proper electrical connection even though the fixture is subjected to vibration when in use.

The principal object of the present invention is the provision of a multiple socket fixture which may be readily assembled without 15 the necessity of soldering any of the current carrying members within the casing.

The preferred form of carrying out my invention is shown in the drawings wherein Fig. 1 is a side elevation of a three-way plug socket embodying my invention; Fig. 2 is a transverse vertical section taken on a plane indicated on the line 2—2 in Fig. 1; Fig. 3 is a longitudinal vertical section through a device taken on a plane by the line 3—3 in Fig. 2; Fig. 4 is a side elevation partly in section showing the relative arrangement of the cooperating parts, and Fig. 5 is a perspective view of a connecting bracket employed with my invention.

20 My invention is shown in connection with a three-way plug socket having a central casing 10 in the nature of a barrel comprising electrical insulating material, for example Bakelite. The barrel is open at the top and bottom and has lateral openings shown at 11 and 12 respectively. The upper end of the barrel may be closed by a head 13 which may be made of Bakelite or other electrical insulating material. The 25 head 13 has a threaded shell 14 and a central contact 15 which provide the electrical inlet to the fixture. The central contact 15 may be insulated from the shell by a layer of electrical insulating material 16.

30 Adjacent the openings 11 and 12, I have shown laterally extending casings 17 and 18 respectively, which provide independent electrical outlets. The electrical outlet in the casing 17 comprises a threaded shell 19 and a central contact 20. The electrical outlet of the casing 18 comprises a threaded

shell 21 and a central contact 22. Similarly the electrical outlet in the casing 10 embodies a threaded shell 23 and a central contact 24.

35 In accordance with common practice, I make the inlet shell 14 adapted to carry current of one polarity and the central inlet contact 16 adapted to carry current of opposite polarity. To connect the contact members in the respective outlets to the inlet contacts, I employ a bracket 25 which briefly embodies a strip of current carrying material, which is so shaped that all of the central contact members can be maintained in proper position by a threaded connection therewith.

40 I have shown the bracket as having parallel faces 26 and 27 which are normal to the axis of the barrel 10, and also as having faces 28 and 29 which are normal to the axes of the casings 17 and 18 respectively. Each of the faces on the bracket has an opening for receiving a threaded member to connect the central contact and maintain it in adjusted position. For example, the central inlet contact 15 embodies the head of a screw 45 which engages a threaded opening 31 in the face 27. Similarly, the faces 26 and 28 and 29 have threaded openings 32, 33 and 34 for receiving the threaded members 35, 36 and 37 respectively. The members 35, 36 and 37 may function to hold the central contacts 24, 20 and 22 respectively in proper position. Thus all of the central contacts 50 are electrically connected together.

55 The inlet contact shell 14 may be electrically connected to the other contact shells by means of a member 40 which is shown as a bar, one end of which is riveted to the shell 60 23 and the other end of which projects through a slot 41 in the plug 13 where it is engaged by the shell 14 when placed in assembled position.

65 To provide an electrical connection between the shells 19 and 21, I have shown connecting strips 42 and 43 which are permanently fastened as by riveting, to the shells 19 and 21 respectively, and which are bent intermediately to provide a friction contact with the shell 23. Thus the shell 14 is electrically connected with the shell 19,

21 and 23 respectively. As shown in Fig. 2, the member 40 is disposed at one side of the bracket 29 wherefore the shells are electrically insulated from the central contacts.

5 To assemble a multiple socket fixture made in accordance with my invention, the head 13 preferably has the shell 14 mounted thereon and the bracket 29 attached thereto by means of the screw 30 and the shell 23 attached to the bracket by the screw 35 carrying the central contact 24, while the rod 40 extends into the shell 14 in snug contact therewith. The casings 17 and 18 having the shells 19 and 21 mounted respectively therein (with the connecting strips projecting parallel with the casing axis, as shown at 42 in Fig. 4) are brought into engagement with the casing 10 and then the connection strips are bent along the inner face of the barrel 10 as shown at 43 in Fig. 4, holding the casings together at these points. The head 13 with the attached bracket and shell 23 is now inserted into the casing 10. The walls of the shell 23 engage the strips 42 and 43 which exert sufficient pressure to make a good electrical connection. Then the shells 19 and 21 are locked in position by the threaded securing members 36, 37 screwing into the bracket 29. These screws also position the central contacts 20 and 22 respectively. The central contacts are suitably insulated from the shells by electrical insulating washers 51. In the case of the central shell 23 an inner insulating washer 50 is also employed to prevent contact between the shell and bracket.

40 From the foregoing description and the drawings, it will be evident that I have provided a multiple socket fixture wherein the electrical and mechanical connections may be made without the use of solder and still a very firmly secured device obtained. While I have illustrated my invention only in connection with a three-way outlet, it will be understood that similar parts may be used in assembling a two-way outlet by making the central casing with only one side opening and omitting altogether one of the side casings and its enclosed parts.

Having thus described my invention, I 50 claim:

1. A multiple socket comprising an insulating cylindrical sleeve open at its opposite ends and having an opening in its cylindrical surface, a second cylindrical sleeve 55 separate from the first, lying at an angle thereto and having the end of its wall concaved to engage the cylindrical surface of the first sleeve about the opening therethrough, metallic shells in the free end portions of the two sleeves, a plug at the other end of the first mentioned sleeve, and means within the sleeves for holding the shells and other contacts in place and for holding the two sleeves together. 60

2. In a device of the character described, the combination of two separable cylindrical sleeves, one cut off concavely to partially embrace the other about an opening through the wall of the latter, a plug at the end of 70 the straight sleeve, a bracket within the straight sleeve secured to the plug by a central screw forming one of the electric conductors, a pair of metallic shells in the two sleeves having flanged inner ends, insulating washers seating on the flanges and central contact screws engaging the washers and screwing into the bracket whereby the sleeves and plug are held together and the shells and contacts are held within the sleeves. 75

3. A multiple socket comprising a cylindrical sleeve of insulating material open at its opposite ends and having a hole through its side wall, a branch sleeve abutting the side wall, screw threaded metallic shells 85 within the adjacent portions of the branch sleeve and first mentioned sleeve, an insulating plug resting against the other end of the main sleeve and having a centering boss 90 therein, a central recess in the inner face of said plug, a metallic bracket seated in said recess, screws carrying the central contacts and engaging said bracket and a central screw passing through the plug into the bracket. 95

In testimony whereof, I hereunto affix my signature,

ISAAC F. GILES.
